UNITED STATES PATENT OFFICE.

EDWIN J. McILVRIED, OF LAKewood, OHIO.

ANVIL.

1,410,692.

Specification of Letters Patent. Patented Mar. 28, 1922.

Application filed March 24, 1920. Serial No. 368,286.

To all whom it may concern:

Be it known that I, EDWIN J. McILVRIED, a citizen of the United States, residing at Lakewood, in the county of Cuyahoga and State of Ohio, have invented a new and useful Anvil, of which the following is a specification.

This invention relates to improvements in anvils more especially designed for heavy work as, for instance, in steam or power hammers.

The primary object of this invention is to so construct the base or body of an anvil on which heavy work is to be done that said body will be able to successfully withstand the great stresses or strains to which it may be subjected and will not be liable to be broken down centrally of the body.

Another object is to form said body of substantially vertical and suitably contoured metal plates arranged side by side and close together and removably secured in place so that plates forming only a portion of said body can be readily replaced, if required, independently of the remainder of the plates.

Another object is to form a seat for the anvil-cap by the tops of the central portions of said plates and to clamp said plates together at such points in relation to said seat that the hereinbefore mentioned body is rendered adequately strong throughout, and a further object is to have each of said plates interchangeable with any other of said plates so that should the seat-forming top edge of a plate show premature wear said plate can be interchanged with any other plate showing less or no wear, to the end of prolonging the life of the anvil-body.

Another object is to render my improved anvil-body simple and durable in construction.

With these objects in view, and to attain any other object hereinafter appearing, this invention consists in certain features of construction, and combinations and relative arrangements of parts, hereinafter described in this specification, pointed out in the claims, and illustrated in the accompanying drawings.

In said drawings, Figure 1 is a side view of an anvil embodying my invention. Fig. 2 is a right-hand elevation in relation to Fig. 1. Figs. 3 and 4 are vertical sections

taken along the line 3—3 and line 4—4, respectively, Fig. 1.

Referring to said drawings, 5 indicates the base or body of an anvil more especially adapted for use as a portion of a steam or power hammer. Said body forms a laminated base, being shown composed (see Figs. 2, 3 and 4) of a substantially horizontal row of substantially vertical plates 6 preferably of steel, and said plates extend transversely of said row and are arranged on edge. Adjacent plates of said row of plates are arranged side by side and contiguous and tied or secured together as will hereinafter appear. The plates 6 extend from end to end and from top to bottom of the body 5. The upper portion of each plate 6 is provided centrally between the ends of the plate, as shown in Fig. 1, with a seat which is formed by the bottom 7 of the lower portion of a recess 8 formed in said plate at the top and centrally between the ends of the plate. The recess 8 in each plate 6 extends laterally through and longitudinally of the plate, and the upper portion of said recess is shown extending endwise of the plate beyond the lower portion of said recess. The recesses 8 in adjacent plates 6 correspond in dimensions and register with each other and are in line longitudinally of the row of plates, and the bottoms 7 of the lower portions of said recesses are flush, as shown in Fig. 3, so that said bottoms form a continuous seat extending from the outer side of one outer-most plate of the row of plates to the outer side of the other outermost plate of said row of plates, and consequently from side to side of the body 5. The end walls 9 of the lower portion of the recess 8 in each plate are shown undercut, (see Fig. 1) and seated on the bottoms 7 of the lower portions of the recesses 8 in the plates 6 is an anvil-cap 10 on which hammer or forging operations are adapted to be performed, and the dovetailed lower portion of said anvil-cap and a gib 12 occupy said portions of said recesses.

Each plate 6 (see Fig. 3) is provided, under the seat 7 formed thereon, with a bolt-hole 14 which extends laterally through the plate. The holes 14 in adjacent plates 6 are arranged in line endwise and correspond diametrically, and said holes are snugly occupied by the shank 15 of a bolt which has its

head 16 arranged at and abutting against the outer side of one of the outermost plates of the row of plates, and said shank extends beyond the outer side of the other outermost plate of said row of plates, and a nut 17 is threaded onto said shank and abuts against said side of the last-mentioned outermost plate. Said nut is tightened against the adjacent plate so that the plates 10 are clamped together by and between said nut and the bolt-head 16.

Preferably the upper portions of the plates 6 are tied or secured together at two points spaced longitudinally of the plates at 15 each side of the seat formed on said plates for the anvil-cap, and at each of said points a bolt having its head 18 (see Fig. 4) arranged at and abutting against the outer side of one of the outermost plates of the 20 row of plates has its shank 19 extending laterally through the plates and beyond the outer side of the other outermost plate of said row of plates, and a nut 20 is threaded onto said shank at and abuts against said 25 side of the last-mentioned outermost plate, and said nut is tightened against said last-mentioned plate so that the plates are clamped together by and between said nut and the head 18 of said bolt.

30 Preferably, also, the end portions of the plates 6 are clamped together below the means comprising the nuts 20 and associated bolts, at points lower than the means comprising the nuts 17 and associated bolts, 35 (see Figs. 1 and 2) by bolts 22 and nuts 23 which are applied to the plates in any approved manner.

By the construction hereinbefore described it will be observed that the plates 6 40 are tied together under the anvil-cap; that said plates are tied together at the sides of the anvil-cap; that the end portions of said plates are tied together at a plurality of points; that each of said plates is interchangeable with any other of said plates, and that by the hereinbefore described 45 structural features and relative arrangements of the parts the objects hereinbefore stated are successfully attained.

50 What I claim is—

1. In an anvil, a body comprising a substantially horizontal row of substantially vertical rigid metal plates which extend transversely of said row and have the tops 55 of their central portions forming a seat for an anvil-cap, and means for removably securing said plates together.

2. In an anvil, a body comprising a sub-

stantially horizontal row of substantially vertical separable rigid metal plates which 60 extend transversely of said row and have the tops of their central portions forming a seat for an anvil-cap, said plates having said central portions clamped together under said seat at a point spaced from said 65 seat and from the bottom edges of the plates, and means clamping the end portions of the plates together.

3. In an anvil, a body comprising a substantially horizontal row of substantially 70 vertical rigid metal plates which extend transversely of said row and have the tops of their central portions forming a seat for an anvil-cap, and means clamping the central portions of said plates together under 75 said seat and comprising a bolt extending through said central portions of the plates, the end portions of said plates being clamped together in proximity to the top and bottom edges of the plates. 80

4. In an anvil, a body comprising a substantially horizontal row of substantially vertical plates which extend transversely of said row and are arranged close together and provided at the top of said row with a 85 seat for an anvil-cap, said plates being interchangeable and tied together at their end portions and under said seat.

5. In an anvil, a body comprising a substantially horizontal row of substantially 90 vertical separable metal plates which extend transversely of said row and have their tops forming a seat for an anvil-cap, said plates being clamped together, and any one of said plates being interchangeable with any 95 other of the said plates.

6. In an anvil, a body comprising a substantially horizontal row of substantially vertical plates which extend transversely of said row, each plate having a recess formed 100 at the top thereof centrally between the ends of the plate and extending laterally through the plate, the recesses in the plates being arranged in line longitudinally of the row of plates and having bottoms forming a seat for an anvil-cap, and the plates being secured together at their end portions and under said recesses. 105

In testimony whereof, I sign the foregoing specification, in the presence of two 110 witnesses.

EDWIN J. McILVRIED.
